UNITED STATES PATENT OFFICE.

KARL TOBIAS KRISTIANSEN GILJE, OF STAVANGER, NORWAY.

PRESSING AND SQUEEZING APPLIANCE.

No. 825,203.

Specification of Letters Patent.

Patented July 3, 1906.

Application filed November 20, 1905. Serial No. 288,294.

To all whom it may concern:

Be it known that I, KARL TOBIAS KRISTIANSEN GILJE, farmer, a citizen of Norway, residing at the city of Stavanger, Norway, 5 have invented new and useful Improvements in Pressing and Squeezing Appliances for Domestic Use, of which the following is a specification.

My present invention has for its object to 10 provide an apparatus serving to press out juice from all sorts of berries, also in the household to press several sorts of eatables, as collared beef, for example.

The apparatus is illustrated in the accompanying drawings, in which—

Figure 1 is a side view, partly in longitudinal section, of the apparatus. Fig. 2 is a plan view in which a part of the press-frame is broken away. Fig. 3 is an end view of the 20 apparatus. Figs. 4 and 5 are end and side views of the automatic stopping device for the rope.

The apparatus comprises a transportable fast-lying part or table 1 and a press-frame 2 25 3 4, which latter after having been placed with its press-plate 2 between the side parts 5 of the table 1 and under the pin 7, passed through a suitable hole 6 in the side stands, rests upon the berry-bag 8 or the ware in 30 question, placed upon the perforated plate 9 on the table 1. The table is extended at 10 and is here provided with a number—for example, five—rope-pulleys 11. The upper part 4 of the press-frame is also extended at 12 35 and has a similar number of rope-pulleys 13. From a hook 14 on the extension 12 a rope 15 passes alternately down and up over all the pulleys 11 and 13 in succession, then down through an automatic stopping device 16, Figs. 1 and 3, and, lastly, upward and around a shaft 17, provided with crank-handle 18 and journaled upon the upper piece 4 of the press-frame. Two screens or 40 guards 19 and 20 cover the pulleys and prevent the rope from passing out of the grooves of the said pulleys.

It will be readily understood that the pressing is caused by turning the shaft 17, whereby on account of the pulley system 45 and the small diameter of the shaft a considerable force is easily obtained on the press-frame. In certain cases also the other end of the rope may preferably be coiled around the shaft 17 instead of being attached to the hook 14.

The last bight of the rope passes through a

stopping device 16. (Shown in Figs. 4 and 5.) This device has a rotatable stopping-pawl 21, the end of which turning against the disk 22 is toothed. By means of the spring 24, 60 coiled around the turning pin 23, the pawl is pressed with its pin 25 against the fixed pin or projection 26 on the disk-frame 27. When, therefore, the rope is pulled so that it tends to turn the disk 22 in the direction of the arrow 28, Fig. 5, the pawl will permit this movement, as it can swing out to the right in the direction of the arrow 29. If, however, the pulling force applied to the rope is released, the pawl 21 immediately will drop 70 into action and jam the rope fast between its teeth and the disk 22, so that the press-frame is held fast in the given position. Therefore the crank 18 may at any time be released and the apparatus may be left while 75 the juice from the bag 8 is flowing through the holes 30 in the plate 9 and through the longitudinal grooves 35 on the under side of the plate. The juice is gathered in a curved channel 31 inside the end piece 32 of the table. From this channel the juice flows to 80 a middle groove 33 and drips off at the lower part of the inclined table 1.

By means of a side projection 34, Fig. 4, the pawl may be swung by hand to the side, 85 so that the last bight of the rope 15 may be passed out of the stopping device 16.

Instead of the stopping device 16 the shaft 17 may, as shown, be provided with a ratchet-wheel 36, so that a pawl 37 may hold 90 the shaft fast against turning back.

According to the thickness of the bag 8 or ware to be pressed the bolt 7 is passed through the most suitable hole 6 and may of course be shifted from one hole to another 95 when the thickness of the bag or ware is gradually decreased during the pressing.

Having now described my invention, what I claim as new, and desire to secure by Letters Patent, is—

1. A press for berries and the like comprising a table, a press-frame consisting of a part substantially parallel with the table and an inclined part connected to the parallel part, pulleys carried by said inclined part, 105 pulleys carried by the table and a rope passing around said pulleys.

2. A press for berries and the like comprising a table having side walls, provided with holes near one end, a removable bolt 110 having its ends resting in opposing holes in the side walls a press-frame having one end

located under said bolt and means for forcing its other end down toward the table.

3. A press for berries and the like comprising a table, a press-frame, means for swiveling one end of the press-frame to the table, a series of pulleys carried by the other ends of the table and press-frame, a rotatable shaft carried by the press-frame, a pawl and ratchet for the shaft, a stopping device carried by the table and a rope having one end secured to the press-frame and passing through the pulleys and the stopping device and having its other end secured to the shaft.

15 4. In combination with the table and press-frame, of the pulleys carried at one end of said parts, a rope passing around said pulleys and a stopping device consisting of a pulley around which the rope passes, a 20 spring-controlled pawl having a toothed end

normally lying adjacent the pulley and projections 25, 26 for preventing movement of the pawl in one direction.

5. A press comprising an inclined table, a perforated plate on said table, said plate having longitudinal grooves on its under side, an end wall on the lower end of the table and said table having a curved channel 31 in its lower end above the wall extending across the table and a longitudinal channel extending from the curved channel to the end of the table and under the end wall, substantially as described.

30 In testimony whereof I have signed my name to this specification in the presence of 35 two subscribing witnesses.
